CLAIM

The ornamental design for a disposable cartridge for a linear surgical stapler, substantially as shown and described.

DESCRIPTION

FIG. 1 is a bottom perspective view of a disposable cartridge for a linear surgical stapler showing my new design;

FIG. 2 is a top perspective view thereof;

FIG. 3 is a rear elevational view thereof;

FIG. 4 is a top plan view thereof;

FIG. 5 is a bottom plan view thereof;

FIG. 6 is an end elevational view thereof, looking from the top of FIG. 1; and

FIG. 7 is an end elevational view thereof, looking from the bottom of FIG. 1.

Fig. 1.

Fig. 6.

Fig. 2.

Fig. 7.
